OIL BURNING STOVE

John B. Olson, Fort Atkinson, Wis., assignor to
James Manufacturing Company, Fort Atkinson,
Wis.

Application January 2, 1937, Serial No. 118,825

3 Claims. (Cl. 126—93)

The present invention relates to oil burning stoves particularly those used for heating poultry houses, brooders, barns, and for home and store furnaces.

5 An object of this invention is to economically burn distillate, kerosene and the like without excessive noise and to provide convenient means for regulating and lighting the stove.

A further object of the invention is to provide 10 convenient means for cleaning the stove and means whereby accidental over-flow of fuel may be drained to a safe place.

Another object of the invention is to provide a 15 design whereby the various parts may be cast without cores and assembled without machining.

A still further object is to provide a flame 20 spreader which is adapted to prevent an excessively noisy fluttering flame, such as is common to burners of the class and to provide means whereby this spreader may be raised for lighting and cleaning and provide a reversible support for this spreader whereby it will return to its operating position by gravity when its supporting member is positioned in one direction, and remain in its raised position when its supporting member is placed in the other position.

Oil stoves are delicate things and if not properly designed frequently become dangerous and wasteful. Generally stated the present invention 30 has for its object to eliminate all of the heretofore objectionable features in stoves of this class and in doing so to increase the efficiency and convenience of the device.

To these and other useful ends this invention 35 consists of parts and combinations thereof or their equivalents as set forth and claimed and shown in the accompanying drawings in which:

Figure 1 is a front elevation of a complete stove especially designed for brooders and the like, a 40 fraction of the drum and stove housing being cut away and a fraction of the burner being shown in section.

Fig. 2 is a transverse section of the burner taken on line 2—2 of Figure 4.

45 Fig. 3 is a sectional view of the burner taken on line 3—3 of Figure 4.

Fig. 4 is a top view of the burner as shown in Figure 2, the flame spreader being down in its working position.

50 Fig. 5 is a top view of a fraction of the device as shown in Figure 1, illustrating the manner of regulating the air supply to the burner.

As thus illustrated the burner drum base ring is designated by number 10. This ring is provided with a suitable flange for the reception of

drum 11, the drum extending to top plate 12. This plate is considerably larger in diameter than the drum and an annular ring plate 13 is provided having the same peripheral diameter as plate 12 and being adapted on its inner surface 5 to engage drum 11.

An outer drum 14 is suitably supported by plate 12 and ring 13, thus providing an outer chamber 15 which surrounds drum 11. An opening 16 is provided on the front side of drum 11 thus providing a passageway from drum 11 into chamber 15.

On the rear of plate 12 and between drums 11 and 14, I provide an outlet pipe 17, thus the heating gas will rise from the burner, pass into chamber 15 through outlet 16 and then pass around drum 11 to the outlet which registers with pipe 17. I provide a conventional, automatic check draft 18 in pipe 17, this device being 20 too well known to require further description.

I provide a burner base 20 which is supplied with suitable supporting legs 21. Base ring 10 is supported on spaced brackets 22 thereby providing an air channel 23 having an inlet as at 24. A circular flange ring 25 is provided forming an 25 inner wall or stop for air channel 23. This ring 25 answers as a centering means for plate 10 as at 26. I provide preferably spaced cut away portions 27 in flange 25. Plate 10 is provided with an inner depression as at 28 forming a seat for 30 burner plate 29.

I provide four valves or projections 31 on the under side of plate 29 which hug the inner wall of flange 25 and move over ports 27 when plate 29 is turned on its support. Thus air may enter 35 at 24, pass between members 10 and 20 and into the burner through ports 27, and the quantity of air admitted to the burner may be regulated by turning plate 29 on its support.

I provide an adjusting shaft 35 which extends 40 through an orifice in plate 10 and having secured thereon, immediately above this plate, a cam 36.

Arms 32 and 33 are made integral with plate 29 and parallel with each other and spaced to thereby loosely embrace cam 36; thus when the cam 45 is turned, plate 29 will be revolved on its seat and projections 31 will be caused to more or less close ports 27.

I provide a flame spreader plate 45 the under side being convex (as indicated), this plate being provided with a support 44 on one side and spaced arms 46 and 47 on the other side each having inturned trunnions which are adapted to seat into pockets 48 and 49 in members 40 and 41. These pockets extend to the bottom of their 55

members whereby when plate 29 is lifted, plate 45 may be removed; thus member 45 is hingedly mounted and when in the position shown in Figure 4, may be swung upward and far enough 5 back so it will rest against the walls of drum 10, thus providing convenient means for access to the burner for lighting the fire and cleaning the burner or for observing the flame.

It has been noted that some operators forget 10 to drop this spreader plate 45 after they have completed the cleaning or lighting task, and I have provided means for avoiding this difficulty if the operator so desires, by simply turning member 29 one half way around so arms 40 and 41 15 embrace cam 36, and when in this position the spreader plate 45 will contact rod 35 before it is in a vertical position and it will therefore fall by gravity when released by the operator.

It will be noted by observing the cutaway section 20 in Figure 4, that valve 31 partially closes ports 27 when cam 36 is in the position shown in this figure; therefore by turning the cam to the left or the right the ports will be covered or uncovered.

25 Member 20 is provided with a central depression or pocket 50 having a feed pipe 51 which is screw threaded into an opening as at 52.

I provide a circumferential trench 53 around pocket 50 the purpose of which is to trap any oil 30 that may overflow the top of pocket 50. I provide also a circumferential channel 54, this channel having a depression 55 positioned under pipe 51. I provide a depression or pocket 56 adjacent depression 55, and an orifice 57 whereby overflow oil trapped in pocket 55 may flow to pocket 56 whence it may flow to a safe place through overflow pipe 58. Thus any oil or fuel that may 35 overflow trench 53, may reach overflow pipe 58.

The outer wall of channel 54 is cut away as at 40 59 thus to make room for pipe 51. In the course of time, if orifice 57 becomes clogged with carbon or other foreign matter, the oil may accumulate until it reaches opening 59 where it will overflow into pocket 56 and escape through 45 overflow pipe 58.

I provide a flange 60, thus forming a shallow 40 channel, the bottom of which intersects the bottom of ports 27; this channel also intersects pocket 56. Thus it will be seen I have provided 50 a central pocket having a fuel oil inlet, a trench around this pocket which is about on the level with the top surface of member 20, and a deep trench 54 which surrounds members 50 and 53 having means whereby to insure against the 55 possibility of leakage of oil from the burner except through the overflow.

Rod 35 extends through member 12 and is 50 bent at a right angle as at 65 having thereon a bracket 66 having two lugs 67 between which member 65 is positioned, thus to key member 65 to bracket 66. Bracket 66 is provided with a plate 68 the outer edge of which forms the arc of a circle.

I provide a bolt 69 having a nut and washer 65 whereby sector 68 may be turned to the right or left and locked into position. Thus the air inlet adjustment can be made from the outside of the drum. Bolt 69 is secured to a lid 70 which forms a cover for an opening in plate 12 for 70 access to the burner; thus when the operator desires access to the burner, cover 70 may be swung sidewise on rod 35 as an axis. If it is found desirable, this lid may be swung in the direction which will open the air ports 27.

75 It will be noted that the opening in plate 29

is somewhat larger than the wall of pocket 50, thus providing an annular passageway 71 whereby the entering air will surround the gas as it escapes from pocket 50, thus insuring complete combustion before the mixture passes from under plate 45.

To start a fire, member 45 is lifted and the well or pocket 50 is filled with fuel oil, some of which may be permitted to flow into trench 53 and a bit of cloth or paper is placed in the well 10 and lighted. The oil is then permitted to burn until there will be sufficient heat in the wall of well 50 to evaporate the fuel oil as it is permitted to flow into this well, and the cloth or paper is then removed as it merely acts as a wick. After 15 the burner begins to operate satisfactorily and the air adjustment has been made, flame plate 45 is permitted to drop into position and lid 70 moved into position, the supply of oil being then regulated either by thermostat control or otherwise. Generally a wick is only necessary when the burner is new or clean, after a few hours use there is enough rough jagged carbon deposit to act as a wick.

As a matter of convenience, I have disclosed 25 my invention as applied to a brooder stove inclosure. It will be understood that it may be used in any conventional type of inclosure and that many minor detail changes in the burner may be made without departing from the spirit 30 and scope of the invention as recited in the appended claims.

Having thus shown and described my invention, I claim:

1. A fuel oil burner of the class described, comprising a central opening, spaced air inlet ports below said opening, an annular ring forming a flame opening revolvably mounted in said opening having depending flanges each adapted to move over one of said ports when said annular ring is turned, a flame spreader positioned over said ring opening having a convexed lower surface and being hingedly mounted at one side to said annular ring, a stop rest on the other side of said spreader cooperating with said hinge to thereby hold the spreader a distance above said ring opening, means on opposite sides of said annular ring transverse to said hinge each adapted to engage a manually operated device positioned on said burner whereby air adjustments may be made in either position of said ring.

2. A fuel oil stove of the class described, comprising a drum and a burner in the bottom thereof having a centrally positioned opening, spaced inlet air ports below said opening, an annular ring forming a flame opening revolvably mounted in said opening and having valves adapted to move across said ports when said ring is turned on its support, a spreader plate having a convexed lower side and being hingedly mounted at one side to said annular ring and having a stop rest cooperating with said hinge to thereby hold said spreader a distance above said ring opening, an opening in the top of said drum having a lid, means for turning said annular ring which extends through the top of said drum adjacent said drum opening and having an adjustable connection to said lid whereby when said lid is turned for access to said drum in one direction, additional air will be supplied to said burner and whereby when said lid is replaced, the air adjustment will be returned to normal.

3. A fuel oil stove of the class described, comprising a drum and a burner in the bottom there-

of having a top plate with an opening, a number of spaced air inlet ports adjacent the periphery of said opening, an annular ring removably mounted in said opening and forming a smaller opening having valves adapted to move across said ports when turned on its mounting, a spreader plate hingedly mounted on and held a distance above said ring, means rotatably supported on said plate adapted to selectively engage either said hinge or said annular ring on its

opposite side from said hinge whereby the ring may be rotated, a rod secured to said rotatably supported means extending vertically and protruding through the top of said drum whereby said ring may be manually turned from the exterior of the drum, said spreader plate having means whereby when said hinge is engaged by said rotatably mounted means it will contact said rod before it reaches a vertical position. 5

JOHN B. OLSON. 10.
